UNITED STATES PATENT OFFICE.

JOHN B. SEMPLE, OF SEWICKLEY, PENNSYLVANIA.

GRENADE.

1,203,062.

Specification of Letters Patent. Patented Oct. 31, 1916.

Application filed August 2, 1915. Serial No. 43,117.

To all whom it may concern:

Be it known that I, JOHN B. SEMPLE, residing at Sewickley, in the county of Allegheny and State of Pennsylvania, a citizen of the United States, have invented or discovered certain new and useful Improvements in Grenades, of which improvements the following is a specification.

My invention relates to improvements in grenades such as are now used in warfare by dropping from air-craft, and my object is to produce a grenade in which effectiveness and cheapness of manufacture are combined, in highest degree.

In the accompanying drawings Figure 1 shows my improved grenade in side elevation; Fig. 2 is a similar view on larger scale, the length of the whole being diminished by the breaking away of part; Fig. 3 is a view partly in side elevation and partly in longitudinal section of a portion of the body of the grenade; and Fig. 4 is a view such as Fig. 3, illustrating a modification in structure.

The first feature of my invention to which I desire to call attention is the great relative length of the grenade. The body proper of the grenade is, as compared with grenades heretofore known, exceedingly long and slender.

The primitive grenade—the bomb—is spherical in shape, just as the primitive projectile—the cannon ball—is spherical.

The cannon ball has been elongated to cylindrical form with this end in view: that, when fired from a rifled gun and so caused to rotate on its axis, it will hold its course more surely, fly farther, and penetrate deeper. And the bomb has been elongated, first to pear shape (or pomegranate shape—hence the name grenade), then to cylindrical shape, that, when properly weighted and provided with steering vane or tail, it may surely fly on its major axis and strike on its head; for the mechanically operating fuse (as distinguished from the time fuse which it has largely displaced) and by which the grenade is exploded, for proper and certain functioning, requires that the grenade be so controlled in flight. Neither projectiles to be fired from rifled guns nor grenades have heretofore been elongated to accomplish other ends than these; and these ends are accomplished, and completely accomplished, in elongation in which the length becomes three or four times greater

than the diameter. I know of no grenade nor projectile constructed, or even proposed, prior to my invention, in which the length was more than five times greater than the diameter.

The grenade of my invention, as distinguished from the grenade of the prior art, is extremely attenuated. Typically, and as shown in the drawings, the length is about twenty-five times the diameter; specifically, its body is forty-three inches long and an inch and three quarters in diameter. The purpose of this extreme attenuation is this: the grenade when it strikes stands forty-three inches high (the ordinary grenade eight or ten inches at most); and, whereas in the use of the ordinary grenade the projected missiles produced by explosion are for the most part soon stopped by surface irregularities, my grenade on explosion sweeps wide areas. And in this connection I desire to point out that this is not a case in which actual dimensions may be adopted at will; it is not a case in which the prior-art structures may be magnified to a degree such that they will stand as high as mine. Quite aside from any question of economy, the limitations imposed upon the grenade designer—limitations such as the carrying capacity of an aeroplane, the muscular strength of the user, etc.—forbid any such magnification as that just suggested. The extreme attenuation which characterizes the grenade of my invention then relates itself in the matter of dimension to actual physical conditions: the depth of furrows in plowed fields, the height of curbstones in city streets, and such like matters. That there is in this matter of actual dimension a point of practical value is evidenced by earlier efforts to overcome the difficulty with grenades such as have previously been made: "jumping bombs" are grenades which on striking rebound and which after rebounding explode while still in the air. Another expedient is to equip a grenade with a suspended weight which, falling faster than the grenade, shall strike the ground first, and on striking shall effect the explosion of the grenade when near but still in vantage position above the surface.

The great length which I give to my grenade (accompanied necessarily, with small diameter) would be quite impractical were it not for the modern development of high explosives. My grenade built forty-

three inches long and an inch and three quarters in diameter has missile-forming wall of steel about three-eighths of an inch thick and a chamber for the burster charge 5 of a scant inch in diameter. A column of black powder an inch in diameter would be utterly incapable of bursting and driving out in a shower of missiles steel walls three eighths of an inch thick, or of any considerable thickness. But even with the use of 10 high explosives the great attenuation which characterizes the grenade of my invention has this result: the force of explosion is not exerted to fragment the casing transversely 15 into pieces of adequate missile forming dimensions. A steel casing having an internal diameter of an inch with walls three eighths of an inch thick will be burst by the detonation of a body of high explosive filling 20 the bore, but it will be torn into long shreds or splinters, and not into suitable grenade missiles.

There is a critical point, not capable (because of the variables involved) of precise 25 definition, but still clearly discernible—a critical point in the development of this idea of attenuation, beyond which (but for my invention) a grenade may not be elongated; for, if it should be attenuated further, transverse fragmentation will be compromised beyond what is practically permissible. That critical point is not reached, nor even approached, in any projectile or grenade of the prior art. But in my grenade, attenuated until the column of burster charge is 30 an inch in diameter, within a wall three eighths of an inch thick, the critical point is far exceeded—indeed, another critical point is measurably approached: the point, 35 namely, beyond which the relatively slender column of burster charge will be ineffective, overcoming the strength of the relatively heavy walls, to fragment the casing and project the pieces with requisite momentum. 40 The critical point first mentioned above I term, in the ensuing claims, "the critical point in the matter of longitudinal fragmentation."

My invention consists in a grenade of the 45 extreme tenuity which I have described, whose casing is discontinuous in the direction of its length. The missile-forming body is cut through, at intervals such as to afford proper dimension of the missiles, in 50 planes of cutting transverse to the length of the grenade. Thus no disruptive strain longitudinally of the structure is requisite, but only the transverse strain which shall tear the casing apart in longitudinally extending breaks and project the pieces in substantially horizontal directions.

I am well aware that both projectiles and 55 grenades have heretofore been contemplated in which the missile forming portions of the casing are built up of balls or rings,

which are of course longitudinally discontinuous; and I am aware also of the expedient of "carameling" the casing—that is to say, scoring it with longitudinal and transverse grooves. But these expedients 70 have been adopted, not to supply or correct or overcome a deficiency in the power of the burster charge, but rather to correct the bad effect of too much power in the explosive. The tendency is to a pulverizing of the casing—breaking of it down to sand or granules and so rendering it ineffective as missile material. On this account the missile-forming material has heretofore been made discontinuous or places of disruption have been 80 predetermined. But never before has this idea of the breaking of the longitudinal continuity of the casing been brought into coördination with the idea of a grenade of extreme length, to accomplish the practical 85 and valuable ends which I attain and have here described.

My grenade is constructed in the manner particularly shown in Figs. 3 and 4. The immediate container for the burster charge 90 and the core about which the effective missile-forming portion of the structure is formed is the relatively thin walled casing 3. Ordinarily this casing will take the form of a steel tube or pipe an inch in diameter and 95 formed of material about one thirty-second of an inch thick; and, as noted above, this pipe will be about forty-three inches long. But the specific figures are given by way of illustration merely, not by way of limitation; 10 they may be departed from widely. Within this casing 3 is contained the burster charge A. Around this casing 3 is applied the material which is to be fragmented by explosion and driven in fragments in all directions. This missile-forming material is applied in a succession of encircling bands, either in a helix 4, as shown in Fig. 3, or in a succession of separate rings 4^a, as shown in Fig. 4. In minuter detail this missile-forming material may be such and so fabricated as desired, to meet the ends in view. In my preferred construction, with effectiveness and economy both in mind, I employ a rolled steel rod three eighths of an inch in 11 diameter, applied as a helix; and, to the end that the missiles may be of more certainly uniform size, this steel rod is weakened by notches at suitably recurrent intervals, as indicated in the drawings at a, b, c, etc. It 12 is manifest that in the size of the rod employed and in the space interval of the successive weakening notches, the constructor may insure beforehand uniformity in the size of the missiles and may determine beforehand their actual size. It is not indeed requisite that my wrapped-on helix or succession of rings which on explosion form the missiles be scored or weakened by cuts or 13 grooves, for the force of explosion is radial

from the center and must inevitably tear each encircling band into parts and drive those fragments in substantially radial directions.

- 5 It is to be remarked of the grenade which I have now described that it is a grenade which is cylindrical and elongate in such marked degree that on explosion relatively few (practically none, indeed) of the missiles will be driven in directions at wide angles from the horizontal (with consequent loss of effectiveness), but substantially all will be driven in substantially horizontal lines—the direction most desired.
- 10 15 In other respects the grenade shown in the drawings possesses known features. The tail 5 is a cloth tail of frusto-conical shape, and open ended, and is secured to the upper or posterior end of the grenade by a frame
- 20 25 6. The tail of course serves to bring the grenade to and maintain it more certainly in vertical position as it falls. The loop 7 of cord or such like material is provided as a means by which a cotter pin 8 may be drawn, which when drawn releases a wind-wheel 9 and allows it to rotate as the projectile falls. The rotation of this wind-wheel effects the arming of the fuse, which normally is unarmed, so that when the grenade
- 30 35 strikes the armed fuse will function and detonation of the burster charge will ensue.

It will be understood on reading the foregoing description that certain features of my invention are not limited in their applicability to grenades as such but are applicable generally to projectiles of other sorts as well as to grenades and I have drawn the ensuing claims accordingly.

- I claim as my invention:
- 40 1. An aeronautical bomb attenuated beyond the critical point in the matter of longitudinal fragmentation and including a missile-forming casing longitudinally subdivided at intervals corresponding to missile dimensions.

2. In a projectile the combination of a body of explosive material and a helix of missile-forming material surrounding the said body and disruptible on the explosion thereof.

3. In a projectile the combination of a body of explosive material and a helix of missile-forming material surrounding the said body, the strength of said missile-forming helix to resist bursting being less than the disruptive strain exerted upon it on the explosion of said body of explosive material.

4. In a projectile the combination of a body of explosive material and a helix of missile-forming material surrounding the said body, said missile-forming helix being weakened at intervals and possessing at such points of weakness a strength to resist bursting less than the disruptive strain there exerted on the explosion of the said body of explosive material.

5. A projectile including in its structure a helix of missile-forming material weakened at intervals in its length and surrounding a burster-charge chamber.

6. A projectile including in its structure a helix of notched steel rod surrounding a burster-charge chamber.

7. A grenade comprising an attenuated central burster charge, a wall surrounding said charge and comprising a longitudinally discontinuous but circumferentially continuous body of missile-forming material, the disruptive capacity of the unit quantity of said charge, which, when detonated, acts upon a circumferential unit length of the missile-forming material, being greater than the resistance of said wall of material to disruption and lateral projection.

8. A projectile including in its structure a tubular chamber and a helix of notched steel rod surrounding said chamber.

In testimony whereof I have hereunto set my hand.

JOHN B. SEMPLE.
